(57) **CLAIM**

The ornamental design for an oral care implement, as shown and described.

DESCRIPTION

FIG. 1 is a right front perspective view of an oral care implement according to the new design;

FIG. 2 is a left front perspective view thereof;

FIG. 3 is a right rear perspective view thereof;

FIG. 4 is a left rear perspective view thereof;

FIG. 5 is a front view thereof;

FIG. 6 is a rear view thereof;

FIG. 7 is a left side view thereof;

FIG. 8 is a right side view thereof;

FIG. 9 is an enlarged top view thereof;

FIG. 10 is an enlarged bottom view thereof;

FIG. 11 is an enlarged right front perspective view of the design; and,

FIG. 12 is an enlarged right rear perspective view of the design.

The broken lines showing the handle illustrate portions of the oral care implement that form no part of the claimed design.

1 Claim, 6 Drawing Sheets
